UNITED STATES PATENT OFFICE.

EDWARD MARLAY DE LAUNE CAROLIN, OF LEEDS, ENGLAND.

VENTILATED BOOT OR SHOE.

1,211,542.

Specification of Letters Patent. Patented Jan. 9, 1917.

Application filed February 21, 1916. Serial No. 79,766.

To all whom it may concern:

Be it known that I, EDWARD MARLAY DE LAUNE CAROLIN, a subject of the King of Great Britain and Ireland, residing at Leeds, 5 in the county of York, England, have invented a new and useful Improvement in Ventilated Boots or Shoes, of which the following is a specification.

This invention relates to improvements in 10 ventilated boots and shoes.

My said invention consists essentially in the provision of a series of approximately parallel unperforated external air passages leading downwardly from inlet openings at 15 or near the top of the boot leg or the shoe upper and having inwardly perforated extensions continuing horizontally and externally around and over the sides and front of the foot, in combination with a similar 20 but inwardly perforated independent air passage or passages leading downwardly from said inlet openings and terminating at the heel, thereby insuring an ample supply of air to all parts of the foot or leg and foot as 25 the case may be.

My invention further consists in the combination, with said air inlets and perforated and unperforated external air passages, of a grooved recessed and perforated insole device 30 whereby the natural movement of the foot within the boot or shoe is utilized to induce a double suction or pumping action and maintain a more or less constant circulation of air throughout the air passages, which 35 air circulation is distributed, by way of the various perforations, over around and under the foot of the wearer, and also down the leg when required.

My invention, though of general application 40 to all types of boot and shoe (either leather, rubber, or canvas), is more especially applicable to waterproof boots such as sea boots, military top boots, trench boots, riding boots, and the like. A comfortable and hygienic boot or shoe is produced, which will 45 be found of great utility in hot countries, and especially at sea.

My said invention is illustrated by way of 50 example in the accompanying drawings, in which:—

Figure 1 is a side elevation of a ventilated rubber top boot having side inlet passages; Fig. 2 is a plan of Fig. 1, in section on the line *aa*; Fig. 3 is a side elevation of a ventilated rubber top boot having rear inlet passages; Fig. 4 is a plan of Fig. 3, in section

on the line *bb*; Fig. 5 is a plan (inverted) of the auxiliary insole device; Fig. 6 is a side view of Fig. 5; Fig. 7 is a cross-section on the line *cc* of Fig. 5.

60

According to my said invention I provide a series of narrow strips A which are applied externally to the boot or shoe in such a manner as to form a series of approximately parallel air passages B leading downwardly

65

from inlet openings C at or near the top of the boot leg or the shoe upper and extending horizontally over and around the sides and front of the foot. These strips A and air passages B are inclosed within a cover D, 70 which is comparatively narrow in width and is likewise extended around the sides and front of the boot or shoe in the form of a brogue or wing cap. In the case of a waterproof rubber boot the strips A are preferably of rubber, the strips and cover being secured externally in position by cementing and vulcanizing under pressure; in the case of a leather or canvas boot or shoe the strips

75

A may be of leather, canvas, whalebone, or other convenient material, the strips and cover being secured externally in any convenient manner, but preferably by stitching. The inlet openings C and the air passages leading therefrom may be arranged at both

80

sides of the boot or shoe (as shown in Figs. 1 and 2), or they may be arranged at the back of the boot or shoe (see Figs. 3 and 4), the boot or shoe in either case retaining its usual and necessary flexibility in front. The 85 air passages B communicate with the interior of the boot or shoe by means of perforations E around the sides and front of the foot only, an independent external air passage B¹ terminating at the heel and with perforations E¹ being utilized for ventilation of the boot leg when required (see Figs. 1 and 4), thus preventing any possibility of the air supply being intercepted and tapped before

90

reaching the foot.

95

Short intermediate strips F may be provided at suitable points if found necessary to prevent sagging of the cover D. Provision may be made, especially in the case of waterproof top boots, for protecting the inlet openings C against ingress of storm water, a projecting rim G being sufficient for this purpose, or an adjustable flap; but in the case of ordinary walking boots and shoes this protecting device may be dispensed with.

105

The strips A may be reinforced by wire or otherwise if desired, and the cover

110

D may likewise be reinforced by metal or other strips or plates at any desired point or points.

In combination with the air inlets and 5 perforated and unperforated external air passages as hereinbefore described, I provide a loose perforated insole H of leather, cork, rubber, or like material, or of such material faced with wool or felt I, this in- 10 sole having grooves J on its edges and undersides in communication with a pair of recesses K at points corresponding to the ball of the foot and the heel. The natural intermittent pressure of the foot and heel 15 thus produces a double suction beneath the grooved recessed and perforated insole H, thus inducing and maintaining a more or less constant circulation of air throughout the air passages B, which air circulation is 20 distributed as required, by way of the various perforations, over around and under the foot of the wearer, and also down the leg when required.

My improved ventilated boot or shoe can 25 be constructed at a comparatively low cost, and the improved ventilating device can also be readily and cheaply applied to existing boots or shoes.

My invention prevents or minimizes the 30 trouble hitherto due to frosty feet in cold weather, and sweaty feet in hot climates.

I claim:—

1. In a boot or shoe, in combination, a 35 series of parallel flexible separated strips applied externally down the leg, extensions of sundry of said external strips continuing horizontally around and over the sides and front of the foot, and a comparatively narrow external cover inclosing the whole 40 of said separated external strips in such a manner as to form a corresponding series

of external air passages open adjacent the top of the leg, sundry of said external air passages being unperforated down their leg portions but inwardly perforated throughout their horizontal extensions around and over the sides and front of the foot, and the remainder of said external air passages being inwardly perforated down the leg and terminating at the heel. 45

2. In a boot or shoe, a series of parallel flexible separated strips applied externally down the leg, extensions of sundry of said external strips continuing horizontally around and over the sides and front of the 50 foot, and a comparatively narrow external cover inclosing the whole of said separated external strips in such a manner as to form a corresponding series of external air passages open adjacent the top of the leg, sundry of said external air passages being unperforated down their leg portions but inwardly perforated throughout their horizontal extensions around and over the sides 55 and front of the foot, and the remainder of said external air passages being inwardly perforated down the leg and terminating at the heel, in combination with a loose perforated and grooved insole having a pair of interconnected recesses at points corresponding respectively to the ball of the foot and the heel, whereby the natural intermittent or alternate pressure of the foot and heel is utilized to induce a double suction and to thereby maintain a constant circulation of air throughout the air passages and perforations. 60

EDWARD MARLAY DE LAUNE CAROLIN.
